FACSIMILE SYNCHRONIZING SYSTEM

Hugh C. Ressler, Richmond, Staten Island, N. Y.,
assignor to Radio Inventions, Inc., New York,
N. Y., a corporation of New York

Application August 15, 1938, Serial No. 224,863

11 Claims. (Cl. 178—69.5)

My present invention relates to methods of and means for synchronizing facsimile recorders and the like with a desired transmitter.

One object of my present invention is to provide means for generating an alternating current synchronized by impulses transmitted to a facsimile receiver and suitable for operating a synchronous motor to drive a facsimile recorder.

A particular object is to provide apparatus in which the stiffness of synchronization increases as the strength of the received synchronizing impulses increases.

Another particular object is to provide a synchronizing system which changes from a passive driven system in the presence of strong synchronizing impulses to an active self-sustaining system in the absence of synchronizing impulses.

Still another particular object is to provide means for converting rectangular impulses into damped oscillations, of applying these damped oscillations to a tuning fork for synchronization purposes and of utilizing the output of the tuning fork for driving a synchronous direct current to alternating current converter the output of which is utilized to drive a facsimile recorder synchronous motor.

These and other objects will be apparent from the detailed description which is given in describing the various figures of the drawings.

In the past, facsimile systems have been synchronized either by transmitting a synchronizing signal along with the picture signal or by employing very stable frequency control means at both transmitter and receiver. In the former type of system the synchronizing signals were used to control the receiving apparatus with a fixed and usually critical degree of control. Too strong a degree of control, in general, causes non-linear distortion of the scanning lines and too weak control permits the system to lose synchronism. Accordingly changes in signal level, especially those caused by fading in a long radio circuit have suffered from alternate distortion and loss of synchronism. In the latter type of system the control apparatus is expensive and even the most elaborate systems drift over long periods of time and hence require considerable attention.

The present invention overcomes these difficulties by employing a relatively stable system with automatic control of both stability of the local system and automatic degree of control by received synchronizing signals.

Briefly, my present system operates in the manner described below. The transmission of facsimile signals is accomplished by cyclic scanning

of an object. A single scanning cycle for instance may last for six tenths of a second and comprise one elemental strip of a subject to be transmitted. The actual picture signal may occupy four tenths of a second or sixty-seven percent of a cycle. The remaining two tenths of a second or thirty-three percent of a cycle may be utilized for picture margin, synchronizing signal and the like. I prefer to use impulses for synchronizing signals of either rectangular shape or of a shape to contain a maximum component of the desired synchronous frequency. These synchronizing impulses are generated in fixed relation to portions of the transmitter scanning cycle.

In the receiver the synchronizing impulses are impressed upon a system resonant to the desired synchronous frequency. The desired synchronous frequency may be 60 cycles suitable for driving a synchronous motor which in turn drives the receiver recording mechanism. The resonant system may be a tuned electrical circuit or it may have a mechanical resonance coupled thru an electrical system as for instance in the case of a tuning fork.

Received synchronizing impulses are impressed upon the electrical or electro-mechanical resonant system and by shock excitation produced damped trains of synchronous frequency voltage. The damping of the damped oscillations may be decreased by using a resonant system with a higher Q, i. e. ratio of L to R or the effective resistance of the system may be reduced by positive feed back or a negative resistance device in shunt.

The synchronous voltage produced in this way is used to operate a reed or interrupter in a direct current to alternating current converter thus producing a source of synchronous alternating current power suitable for driving a synchronous motor at the receiver recorder.

In a preferred form of my present system a tuning fork is coupled to a thermionic vacuum tube amplifier in such a way that energy is fed back from the output of the amplifier to the input thru the mechanical impedance of the tuning fork. The feed-back circuit is proportioned and coupled in such a way that it is regenerative and may be made to increase the Q of the tuning fork or generate sustained oscillations by varying the amplifier gain as by varying the amplifier tube bias. When synchronizing impulses are fed to this circuit under conditions of regeneration, damped oscillations are produced of synchronous frequency, and if the bias is changed to cause the system to oscillate under the joint influence of feed-back and synchronizing signals, the syn-

chronizing impulses serve to synchronize the frequency of oscillation. The strongest synchronization takes place just below the point of self-oscillation. By rectifying either the amplifier output or the received impulses and using the filtered rectifier output to control the amplifier gain, the system may be made to change from a passive system generating damped oscillations or tightly controlled synchronous oscillations to an active system generating steady unsynchronized oscillations depending on the amplitude of synchronizing impulses present in the input. In this way the system operates as a tightly synchronized driven system in the presence of strong synchronizing impulses, as a weakly synchronized self-oscillating system in the presence of weak synchronizing impulses and as a stable non-synchronized self-oscillator in the absence of synchronizing impulses. This mode of operation is particularly valuable in connection with long radio circuits where fading may destroy the synchronizing impulses for short periods of time, but since the system then becomes self-sustaining only small drifts will take place before the signal returns. This system thus has the advantage that the degree of control of synchronizing signals depends on their amplitude whereby the system is not critical in adjustment and does not lose synchronism on momentary loss of signal.

The synchronizing signal sent out from the transmitter may be a group of waves of the desired frequency which, except for a transient term, are essentially sine waves. In the receiver this synchronizing signal may be fed to the generated tuning fork. The tuning fork when made less sensitive to external signals is, of course, more stable. The synchronizing signal, consisting of several cycles of the desired frequency, acts to correct the tuning fork frequency a slight amount during each cycle of synchronizing signal. Since these are several cycles of correcting signal, the fork frequency may be made very stable, minimizing disturbing effects of stray signals and yet maintaining good average synchronism.

Another mode of operation is to transmit on a radio carrier or over a line substantially rectangular impulses which may be modulations of sub-carrier signal for synchronization purposes. In the receiver these impulses are rectified producing unidirectional rectangular impulses or corresponding groups of sub-carrier signals which are impressed on an electrical circuit tuned to the desired synchronous frequency. The impulses by shock excitation generate damped wave trains of synchronous frequency voltage which may be used to synchronize the tuning fork as described above for groups of sine wave synchronizing.

In the drawings:

Fig. 1 shows a circuit diagram of the present synchronizing system.

Fig. 2 shows a modification of the present synchronizing system.

Fig. 3 shows various signal waves useful in explaining the operation of the synchronizing system.

Fig. 4 shows further explanatory waves.

Fig. 1 shows a circuit of one form of the present synchronizing system. A cascade two stage amplifier employing thermionic vacuum tubes 1 and 2 is connected with its input across a tuned electro-magnet 10 and its output across a second tuned electro-magnet 12. Electro-magnets 10 and 12 are coupled by coupling each magnet-

ically to a tine of the tuning fork 9. The amplitude of oscillation or the amount of regeneration thus produced is controlled by rectifier 3. The generated signal controls a direct current to alternating current converter by means of amplifier tube 4. The alternating current output of the converter is used to operate the synchronous motor 66 which turns the mechanism of the facsimile receiving scanner 68. The facsimile receiver 5 supplies picture signals to the scanner 68 and synchronizing signals to the tuning fork through the use of electromagnet 8.

The operation of the system of Fig. 1 will now be traced in detail. While the system may be operated from a wire line signal, a radio system 15 will be described. Radio signals modulated with facsimile picture signals and synchronizing signals are picked up on antenna 7 and amplified and detected by the facsimile receiver 5. Picture signals from the receiver are applied to receiving 20 scanner 68 over leads 86 and 87 and synchronizing signals are applied to tuning fork 9 by means of electro-magnet 8.

The cascade amplifier, including thermionic vacuum tubes 1 and 2, is used to regenerate tuning fork 9 and may be operated to cause self-sustaining oscillations. Tube 1 includes heater 22, cathode 17, control grid 18, screen grid 19, suppressor grid 20 and plate 21. A plate battery 43 is shown energizing electrodes of tubes 1 and 2 although other well known means may be used. Heater voltage supply for heaters 22, 36, 52, 89 and 90 is not shown, but will be understood to be any well known means. Plate 21 is energized from battery 43 through the decoupling resistor 38, interstage coupling transformer 30 and plate current meter 33. Screen 19 is energized from the voltage supply 43 through the decoupling resistor 88 and the screen dropping and decoupling resistor 28. Cathode 17 receives a bias from the voltage drop across resistor 25 due to the cathode current plus the current through resistors 23 and 24. The plate voltage is by-passed by condenser 27 and the screen voltage is by-passed by condenser 26. The voltage across electro-magnet 10 is tuned by condenser 11 is applied to grid 18. Coupling transformer 29 is connected with its primary connected to plate 21 and its secondary connected to grid 38 of tube 2. The secondary 31 is tuned to the synchronizing frequency by condenser 32. Heater 36 of tube 2 energizes cathode 37. Cathode 37 receives a bias due to cathode current flowing thru resistor 35 connected to common ground 6 and by-passed by condenser 34. Plate 39 of tube 2 is energized from voltage source 43 through primary 40 of output transformer 41. Output transformer 41 receives signal voltage from plate 39 and feeds rectifier 3 from its secondary 42. Secondary 42 is shunted by resistor 44. Rectifier 3 comprises cathodes 47 and 48 energized by heaters 89 and 90 and anodes 46 and 45. Lead 91 applies a bias to cathodes 47 and 48 from the drop across resistors 24 and 25. Signal voltage across secondary 42 is applied between anodes 45 and 46 and cathodes 47 and 48. Rectified voltage is developed by the charges produced in condenser 50 leaking off through resistor 49. The anode end of resistor 49 which is connected between anodes 45 and 46 and ground 6 will become negative with respect to ground due to rectified currents flowing in it and this negative voltage is applied to grid 18 through filter resistor 70 and the winding of electro-magnet 10. Condenser 11 cooperates with resistor 70 to smooth the rectified voltage applied to grid 18. The sig-

nal voltage across secondary 42 is also applied to electromagnet 12 tuned by condenser 13 through control resistors 15 and 16. In addition, the signal across secondary 42 is applied to grid 53 of amplifier 4. Amplifier 4 includes heater 52, energizing cathode 51, control grid 53 and plate 54. Cathode 51 is connected to ground 6 through bias resistor 55 which in turn is by-passed by condenser 56. Plate 54 is energized from a plate voltage source 57 which is shown as a battery, but not limited to such. The plate current of tube 4 is caused to flow through the interrupter electromagnet 58 and hence causes reed 59 to vibrate in response to signals applied to grid 53. The mid-point of winding 65 of the auto-transformer 64 is connected to one side of a source of direct current power by means of lead 63. The other side of the source of direct current power is connected alternately to opposite sides of winding 65 through reed 59 and the alternating contacts 60 and 61. Thus an alternating current is caused to flow in winding 65 in step with the signal voltage applied to grid 53 since electro-magnet 58 operates the reed 59 at this frequency. If no direct current were permitted to flow through electromagnet 58 the alternating frequency would be doubled. The synchronous motor 66 is supplied with alternating current voltage from transformer 64 through taps 92 and 93. The synchronous motor 66 is mechanically coupled to drive receiving scanner 68.

In operation, tuning fork 9 is set in vibration by pressing starting button 14, causing a surge of current to flow through the winding of electromagnet 12. This surge of current magnetizes magnet 12 attracting one tine of fork 9. The motion of this tine induces a motion in the other tine and hence a voltage in the winding of electro-magnet 10. This voltage is amplified by tubes 1 and 2 and reapplied to fork 9 through electro-magnet 12. Fork 9 acts as a mechanical filter and with sufficient gain in the amplifier and proper polarity of electro-magnets 10 and 12 self-sustaining oscillations will be set up at a frequency very close to the natural frequency of the fork 9. Tuning electro-magnets 10 and 12 by means of condensers 11 and 13 to the frequency of the fork assists the production of oscillations. After the system has started to oscillate, button 14 is released and a partial control of oscillation amplitude may be affected by adjustment of control resistance 16 in series with fixed control resistance 15. Other well known methods may be employed for initially setting the amplifier gain as for instance by varying the turns ratio of transformer 29-30-31. With the system oscillating an alternating current, voltage will be fed to rectifier 3. The rectified direct current produced by rectifier 3 is applied to grid 18 and here reduces the gain of the amplifier. This reduction in amplifier gain tends to reduce the amplitude of oscillation and a stable automatically controlled oscillation amplitude results.

Now, if synchronizing signal voltage of the same frequency as the fork frequency, or of nearly the same frequency is applied to fork 9 by means of electro-magnet 8, the fork frequency may be locked in step with the synchronizing signal frequency. With large synchronizing signal voltage applied to electro-magnet 8, the system may be adjusted so that it will not oscillate in a self-sustaining manner at the same amplifier gain or net bias on grid 18. In this condition synchronization is very tight

and exact. If now the synchronizing signal is removed due to fading of the radio signal, the amplitude of oscillation of the fork will start to die out. As it dies out the rectifier 3 receives a smaller and smaller signal voltage and produces a decreasing bias on grid 18. A point is finally reached at which the gain of the amplifier is increased until self-sustaining oscillations are again produced and the system continues at the natural frequency of fork 9. If fading periods are short, the system will drift but little until synchronizing signals are again produced and the system returns to its initial tightly synchronized condition.

The operation is much the same if synchronizing signals are sent for short intervals interspersed with the facsimile signal, as for instance, at the end of each line. When the synchronizing signal is received, the frequency is corrected and, during the picture signal interval, the fork carries the system along.

The synchronous voltage produced in the fork amplifier controls the direct current to alternating current converter as described above, and runs the synchronous motor 66, and hence scanner 68, in step with the received synchronizing signal.

The level of received synchronizing signal at which the self-sustaining condition of the fork oscillation system takes place may be predetermined by adjustment of control resistor 16 or by adjustment of the amplifier gain.

One form of composite picture signal and synchronizing signal wave suitable for operating the system as described is shown in Fig. 4. A complete scanning cycle is represented by synchronizing signal K plus picture signal I where I represents one line of the picture being transmitted. The number of cycles in the synchronizing signal K may be determined by practical considerations. The larger the number of cycles the more stable may be the fork and still by a small correction on each cycle reach exact synchronism at each synchronizing interval. If the synchronous frequency is 60 cycles and the synchronizing interval is two tenths of a second, twelve cycles of synchronizing frequency may be transmitted during each interval. The effectiveness of the synchronization also increases rapidly as the line frequency becomes higher and more nearly equal to the synchronizing frequency.

Fig. 2 shows a modified circuit in which most of the component circuit of Fig. 1 are shown in block diagram. Tube 72 with its associated circuits has been added to the system.

In Fig. 2 a facsimile receiver 5 receiving radio signals by means of antenna 7 and ground 6 receives, amplifies and demodulates the facsimile modulated carrier signals and if necessary separates synchronizing and picture signals. It will be understood that as in the case of Fig. 1 receiver 5 may be replaced by suitable apparatus for operation from a wire line. In Fig. 2 the synchronous motor 66 and receiving scanner 68 of Fig. 1 are represented by synchronous motor and receiving scanner block 85. Similarly the various components of the converter system are represented by block 84 and the tuning fork amplifier and rectifier control system by block 83. The tuning fork 9 and its associated electro-magnets 8, 10 and 13 are repeated for purposes of explanation in Fig. 2. The circuit of Fig. 2 is especially adapted to operate from a rectangular or other impulse type of synchronizing signal as shown at a in Fig. 3. These synchronizing

impulses are applied to primary 80 of transformer 79 the secondary 81 of which is tuned to the desired synchronous frequency, as for instance 60 cycles, by condenser 92. The synchronizing impulses applied to transformer 79 by shock excitation generate damped oscillations in the secondary, as shown at *h* in Fig. 3. These damped oscillations are applied to grid 74 of amplifier tube 72. Amplifier tube 72 may be a 5 triode as shown having heater 16, cathode 75, control grid 74 and plate 73 or any suitable amplifier. Cathode 75 may receive a bias thru the drop in resistor 17 by-passed by condenser 18. Plate voltage for amplifier 72 may be supplied 10 by battery 82 or its equivalent. The damped oscillations applied to grid 74 are amplified and applied to fork magnet 8 by placing it in series with plate 73. With a bias, as battery 82, in series with magnet 8, its operation on tuning 15 fork 9 is at fundamental frequency while without such bias its control will be exerted at twice fundamental frequency. Thus, magnet 8 receives damped oscillations of synchronous frequency voltage instead of the type of signal shown in 20 Fig. 4, but the remainder of the system is operated and synchronizes in a manner similar to the system described in connection with Fig. 1.

In both Figs. 1 and 2 the synchronizing signals are shown applied to fork 9 by means of a 30 tertiary magnet 8. This method of synchronous signal application causes the fork to act as a filter selecting the desired synchronous frequency components and eliminating the picture signal.

Fig. 3 shows at *e* a synchronous impulse *a* 35 space *b* picture signal *c* and second space *d*. At *f* is shown the modulated carrier resulting from modulation by signals of line *e*. At *g* is shown the received and rectified carrier voltages which should be a reproduction of line *e*. On line *h* 40 is shown the damped oscillations resulting from the synchronizing impulse *a* as described in connection with Fig. 2. While no sub-carrier waves have been shown, it will be understood that the picture signal and synchronizing signals shown 45 may be impressed on a suitable sub-carrier before transmission and that this sub-carrier, usually a high audio frequency, may be retained to any desired point in the receiver.

It is not intended to limit the invention to the 50 particular embodiment shown but only to those embodiments falling within the spirit and scope of the invention as set forth in the appended claims.

I claim:

55 1. In a facsimile synchronizing system, the combination of, means for receiving synchronizing signals, a regenerated tuning fork, means for automatically varying the degree of regeneration as a function of the amplitude of said synchronizing signals.

2. In a facsimile synchronizing system, the combination of, means for receiving synchronizing signals, a regenerative tuning fork circuit, means for automatically increasing said regeneration to the point of self-oscillation in response to synchronizing signals below a predetermined level.

3. In a facsimile synchronizing system, the combination of, means for receiving synchronizing signals, a regenerative self-oscillatory tuning fork, and means for automatically decreasing the regeneration below the point of self-oscillation in the presence of received synchronizing signals of greater than a predetermined amplitude.

75 4. In a synchronizing system, the combination

of, synchronizing signal receiving means, low decrement vibratory means, electrical means for automatically varying the decrement of said vibratory means as a function of the amplitude of received synchronizing signals, and means for controlling the frequency of vibration of said vibratory means in accordance with synchronizing signals having amplitudes greater than a predetermined amplitude.

5. In a facsimile receiving system, means for 10 maintaining synchronism with a desired transmitter comprising, in combination, a facsimile receiver, a tuning fork composed of magnetic material, a direct current to alternating current inverter including a magnetic reed for determining 15 the frequency of said alternating current, a receiving scanner, a synchronous motor driven by said alternating current for driving said receiving scanner, an amplifier including input and output circuits, electromagnetic means coupling said input with said fork, electro-magnetic means coupling said output with said fork, electro-magnetic means coupling said receiver with said fork, and electro-magnetic means coupling 20 said amplifier output with said reed whereby the speed of operation of said receiving scanner is determined by signals traversing said receiver.

6. In a facsimile receiving system, means for maintaining synchronism with a desired transmitter comprising, in combination, a facsimile 30 receiver, a tuning fork composed of magnetic material, a direct current to alternating current inverter including a magnetic reed for determining

the frequency of said alternating current, a receiving scanner, a synchronous motor driven 35 by said alternating current for driving said receiving scanner, an amplifier including input and output circuits, electromagnetic means coupling said input and output with said fork, electromagnetic means coupling said receiver with 40 said fork, electromagnetic means coupling said amplifier output with said reed whereby the speed of operation of said receiving scanner is determined by signals traversing said receiver, and means for rendering said tuning fork and amplifier a self-sustaining oscillatory system for 45 all received signals below a predetermined level.

7. In a facsimile receiving system, means for maintaining synchronism with a desired transmitter comprising, in combination, a facsimile 50 receiver, a tuning fork composed of magnetic material, a direct current to alternating current inverter including a magnetic reed for determining

the frequency of said alternating current, a receiving scanner, a synchronous motor driven 55 by said alternating current for driving said receiving scanner, an amplifier including input and output circuits, electromagnetic means coupling said input with said fork, electromagnetic means coupling said output with said fork, electro-magnetic means coupling said receiver with 60 said fork, electro-magnetic means coupling said amplifier output with said reed whereby the speed of operation of said receiving scanner is determined by signals traversing said receiver, 65 and means interposed between said receiver and said third electromagnetic means for converting at least a portion of said received signals into damped oscillations.

8. In a motor driven facsimile receiving system, a system for synchronizing said motor with received synchronizing signals including in combination, an oscillatory device, a controllable regenerative circuit coupled to said oscillatory device capable of generating sustained oscillations.

5 tions at substantially the natural frequency of said oscillatory device at regenerative levels above a critical value, a control circuit connected to a source of received synchronizing signals for varying the regeneration in said regenerative circuit above and below said critical value in a sense wherein increased received synchronizing signal amplitudes produce decreased regeneration, and an alternating current generator frequency controlled by said oscillatory device for operating said motor.

9. In a motor driven facsimile recording system, a system for operating said motor in synchronization with a predetermined synchronizing signal including in combination, an oscillatory device, a controllable regenerative circuit coupled to said oscillatory device for generating sustained oscillations at substantially the natural 10 frequency of the oscillatory device at regenerative levels above a predetermined value, a regeneration control circuit connected to a source of synchronizing signals for decreasing said regeneration below said critical value for amplitudes of synchronizing signal greater than a 15 predetermined value, an alternating current generator for operating said motor, and circuits for controlling the frequency of said alter- 20

25 nating current from the frequency of said oscillatory device.

10. The method of operating a tuning fork in a regenerative circuit in the presence or absence of synchronizing signals for controlling the speed of a motor which includes synchronizing said fork strongly in the presence of substantial amplitudes of synchronizing signal, of automatically increasing the regeneration at least to the point of self-oscillation with said fork in the absence 10 of substantial amplitudes of synchronizing signal, and of operating said motor in synchronism with said tuning fork.

11. The method of operating a synchronizing system including an alternating current synchronous motor, a direct current to alternating current converter, and a regenerated tuning fork system which includes, applying synchronizing signals to said tuning fork system, utilizing said synchronizing signals to control the average regeneration in said tuning fork system, utilizing signals derived from said tuning fork to control the frequency of alternating current generated by said direct current to alternating current converter, and operating said synchronous motor from alternating current derived 15 20 25 from said converter.

HUGH C. RESSLER.
